United States Patent Office

Des. 178,897
Patented Oct. 2, 1956

178,897

MOTOR BASE FOR LIQUEFIER OR SIMILAR ARTICLE

Walter E. Moore, Belnol, Mo., assignor to Knapp-Mon-
arch Company, St. Louis, Mo., a corporation of Dela-
ware

Application September 6, 1955, Serial No. 37,795

Term of patent 14 years

(Cl. D89—1)

Figure 1 is a front elevational view showing a motor base for a liquefier or similar article showing my new design;

Figure 2 is a top plan view of the same;

Figure 3 is a side elevation view of the same looking from the right of Figure 1; and

Figure 4 is a rear elevation view of the same.

I claim:

The ornamental design of a motor base for a liquefier or similar article, substantially as shown.
